J. H. STUBBS

REEL OR SWIFT FOR USE IN THE WINDING OF TEXTILE YARNS

Filed Dec. 24, 1925

UNITED STATES PATENT OFFICE.

JOSEPH HETHERINGTON STUBBS, OF ANCOATS, MANCHESTER, ENGLAND, ASSIGNOR
TO JOSEPH STUBBS LIMITED, OF ANCOATS, MANCHESTER, ENGLAND, A LIMITED
LIABILITY COMPANY OF GREAT BRITAIN.

REEL OR SWIFT FOR USE IN THE WINDING OF TEXTILE YARNS.

Application filed December 24, 1925, Serial No. 77,594, and in Great Britain October 1, 1925.

This invention relates to reels or swifts on which yarns are to be wound or on which they are to be placed in the hank form for rewinding therefrom, and is particularly applicable to swifts whereon artificial silk yarns are to be wound from the package in which the said yarns have been spun, for instance, a cake as it comes from the spinning box in one of the viscose processes. The artificial silk at that stage is very liable to damage, being fragile and having little cohesion, and such damage does take place in removing the wound hank from the swift for the subsequent treatment necessary.

My invention has for object a means for ensuring that a hank may be safely removed from a swift without danger of rupture of any of the yarn coils, and in carrying the said invention into effect I form the swift with arms which are all slideable radially, with means for sliding such arms simultaneously. A hank can thus after winding be left absolutely loose on the yarn bearing arms, for easy removal.

Although the invention is exceedingly useful for the purpose just stated, it can be equally well applied, as will be understood, to reels on which hanks of any fragile yarn have to be placed for winding off, as such hanks can be safely and rapidly put in position on the reels by sliding the reel arms inwardly, and then outwardly after the hank is in position to tighten the latter sufficiently.

The invention, in a very convenient manner of carrying it into effect, in a swift for the winding into hanks of artificial yarns, will now be described with reference to the accompanying drawings, in which Figure 1 is a side elevation of a swift showing the arms in two positions; and Figure 2 is a horizontal cross section taken centrally of Figure 1.

Referring to the figures, 3 is a squared driving shaft having the circular necks 4 two discs 5 being secured on this squared shaft by the grub screws 6. These discs will be referred to later. The hub 7 of the swift is of wood, this hub having a central bore. On each end of this hub are screwed the hub flanges 8 each flange being of sheet metal and having their peripheral edges turned over as shown in the figures, the turned over edges being slotted as at 9 for

the passage of a swift arm 10 and to maintain the same against angular movement in relation to the hub. Each hub flange 8 is radially slotted as at 11 and the inner end of each arm 10 of the swift is returned at 12—see Figure 2—and enters a slot 11 being 55 slidably secured therein by the distance collar 13 and the nut 14. Guides 15 are punched from the metal of each hub flange on either side of an arm 10, these punched out guides 15 being perpendicular to the face 60 of the flange 8. Holes 16 may be punched in each hub flange 8 for lightness.

Upon each returned end 12 of an arm 10, and held in place thereon by the distance piece or collar 13 and the nut 14, is pivoted 70 the end of a link 17 the other end of which is pivoted upon a headed screw 18 in the adjacent disc 5. Normally, when the arms 10 are fully extended outwardly, a slot 11, an arm 10, and a link 17 lie on the same radius 75 line of a hub flange 8.

To one of the discs 5 is secured as shown in the figures an arm 19, cranked so that its free end lies closely adjacent to the hub flange on that side, and having fitted on the 80 said free end the handle 20. A pin or the like 21 on the cranked arm fits, by the resiliency of the metal of such arm 19, within either of two holes 22 and 23 in the adjacent hub flange. More than two such holes may 85 be provided.

As thus described and as shown in full lines in Figure 1 and in section in Figure 2, the arms are fully extended and the swift is in the winding position. To remove a 90 wound hank, handle 20 is pulled away from the hub flange 8, the wooden hub 7 is firmly grasped and the disc 5 to which the handle is attached is given angular motion, the disc on the other side receiving the same motion. 95 The swift arms 10 are thus drawn inwardly, and the links 17 and swift arms 10 assume the position shown in dotted lines in Figure 1—in this figure the pivot pin or screws on the discs are omitted for clearness—and the 100 handle being released the pin 21 enters hole 23 in the hub flange adjacent, thus holding the arms in the retracted position. The hank is then doffed and the swift put into position for a fresh winding operation. 105

The position of the hank yarn when the arms 10 are fully extended is shown in broken lines in Figure 1; in the retracted

position of the arms 10, the yarns are shown in dotted lines.

For clearness of description I have referred to the arms 10 on each side of the swift as being separate. Two opposing arms however are preferably formed in one, the central portion being cased with ebonite or like material 24 which will withstand the action of the corrosive acids in artificial silk yarns as they come from the spinning process.

I claim:—

As a means for the winding of fragile yarns into or from hank form, a squared driving shaft, discs fixed upon the said shaft, a central tubular wooden hub mounted upon the shaft between the discs and having end flanges concentric with the said discs, the shaft being capable of angular

movement relatively to the hub and its flanges when the said hub is held to prevent its movement, a spring handle with pin mounted on one of the discs and adapted to engage in holes formed on radii of an adjacent hub flange, arms radial to the hub and bearing yarn carrying surfaces at their outer ends the inner ends being returned and such returned ends slidably engaging in radial slots in the hub flanges, means for slidably securing the returned ends within such radial slots, supports in the flanges to preserve the radial relation of the arms thereto, and a pivoted link between each such arm and a point on a radius of an adjacent driving shaft disc.

In testimony whereof I have hereunto set my hand.

JOSEPH HETHERINGTON STUBBS.
